DESIGN FOR A BOTTLE

John H. Steuernagle, Du Bois, Pa., assignor to Brockway Glass Company, Inc., Brockway,
Pa.

Application May 2, 1936, Serial No. 62,436

Term of patent 7 years

To all whom it may concern:

Be it known that I, John H. Steuernagle, a citizen of the United States, residing at Du Bois, in the county of Clearfield and State of Pennsylvania, have invented a new, original, and ornamental Design for a Bottle, of which the following is a specification, reference being had to the accompanying drawing forming part thereof.

Fig. 1 is a front elevation of a bottle showing my new design;

Fig. 2 is a side elevation;

Fig. 3 is a bottom plan view; and
Fig. 4 is a horizontal sectional view taken about on line 4—4 of Fig. 1.

The faces of the bottle opposite to those shown in Figs. 1 and 2 are the same as the faces which appear in each of those figures respectively.

I claim:

The ornamental design for a bottle substantially as shown and described.

JOHN H. STEUERNAGLE.
